UNITED STATES PATENT OFFICE

2,502,613

HEAD SPACER GAUGE FOR RIFLES

Nicholas C. Zanolio, Durango, Colo.

Application January 31, 1947, Serial No. 725,444

7 Claims. (Cl. 33—174)

1

My invention relates to measuring tools and more particularly to gauges for measuring the head space in rifles.

The object of my invention is to provide a gauge consisting of a measuring rod removably fastened to a base shaped like a cartridge and adapted to extend through the bore of a rifle barrel.

Another object of my invention is to provide a gauge of the character indicated above, the measuring rod whereof is adapted to serve as an anvil of a micrometer removably attached to the rifle barrel.

Other objects of my invention may appear in the following specification describing my invention with reference to the accompanying drawings illustrating a preferred embodiment of my invention.

It is, however, to be understood, that my invention is not to be limited or restricted to the exact construction and combination of parts described in the specification and shown in the drawings, but that such changes and modifications can be made, which fall in the scope of the claims appended hereto.

In the drawings:

Figure 1 is a longitudinal sectional view through a rifle barrel, to which a head space gauge according to my invention is attached.

Figure 2 is a sectional view taken on line 2—2 in Figure 1.

Figure 3 is a fragmentary elevational side view, partly shown in section, of the assembled measuring rod of the gauge according to my invention, and

Figure 4 is a sectional view taken on line 4—4 in Figure 1.

Referring now in detail to the drawings, the head space gauge forming the subject matter of my invention, comprises a measuring rod 10 consisting of a base 11 shaped like a rifle cartridge and fitting closely into the firing chamber 12 of a rifle, and a round rod 13 threadedly connected with the forward reduced portion 14 of the base 11.

The base 11 and the rod 13 are assembled by screwing them tightly together and this assembly is inserted in the rifle barrel 15 from the rear by removing the rifle bolt 31.

After the assembly has been inserted the bolt 31 is replaced again.

A sleeve 16 fits slidably on the rod 13 and fits tightly into the muzzle of the barrel 15.

A diametrically extending hole 17 is provided in the rod 13, so that this hole 17 will be located

2

at a distance in front of the sleeve 16, when this sleeve is positioned in the rifle muzzle, and the assembled measuring rod 10 is arranged in the rifle, so that the base 11 is in its foremost possible position.

A helical spring 18 is arranged, so that it surrounds the rod 13 and abuts the forward end of the sleeve 16. A pin 19 is inserted in the hole 17 and the spring 18 engages this pin and urges the measuring rod 10 forwardly into its foremost possible position.

An adjusting bar 20 is located slidably in a sleeve 21 formed on the lower portion of a barrel clamp 22, which is slotted longitudinally as indicated 23 to enable the clamp to slide over the sight 24 on the rifle barrel. The upper wing ends 25 of the clamp are adapted to be forced together by means of a bolt 26 and a wing nut 27 on said bolt to secure the clamp in position on the rifle barrel 15.

A set screw 28 in the wall of the sleeve 21 is adapted to engage the adjusting bar 20 in adjusted position.

On the forward end of this adjusting bar a micrometer 29 of any well known make and construction is secured or formed.

The anvil of this micrometer is removed and the forward end of the rod 13 extends through the hole in the micrometer usually accommodating the foot pin of the anvil.

To measure the head piece of the rifle, the micrometer screw 30 is set to touch the forward end of the rod 13. The setting of the micrometer is noted. Then the rod 13 is forced rearwardly until the rear surface of the base 11 contacts the bolt 31. The micrometer 30 is reset to touch the forward end of the rod 13 in its new position and this setting of the micrometer is read and deducted from the first reading. The result is equal to the head space of the rifle.

Having described my invention I claim as new and desire to secure by Letters Patent:

1. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having an end engaging said spring means for maintaining said base in full forward simulated firing

position, including means for providing an opposing force engagement for the other end of said spring, said spring being stressable to permit said rod to be thrust rearward manually the full extent determined by the head space to be measured.

2. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having an end engaging said spring engaging means for maintaining said base in full forward simulated firing position, including means for providing an opposing force engagement for the other end of said spring, said spring being stressable to permit said rod to be thrust rearward manually the full extent determined by the head space to be measured, including means disposed adjacent the outward end of said rod for measuring the travel thereof between full forward position to full rearward position as determined by said head space.

3. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having an end engaging said spring engaging means for maintaining said base in full forward simulated firing position, including means for providing an opposing force engagement for the other end of said spring, said spring being stressable to permit said rod to be thrust rearward manually the full extent determined by the head space to be measured, including support means disposable at the muzzle end of said rifle, and a micrometer head carried by said support means, said micrometer head having a reciprocal element engageable with the outer end of said rod for measuring the length of said travel.

4. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having an end engaging said spring engaging means for maintaining said base in full forward simulated firing position, including means for providing an opposing force engagement for the other end of said spring, said spring being stressable to permit said rod to be thrust rearward manually, the full extent determined by the head space to be measured, wherein said rod and base are threadedly connected to permit attachment or separation thereof when the base is in firing position.

5. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having an end engaging said spring engaging means for maintaining said base in full forward simulated firing position, including means for providing an opposing force engagement for the other end of said spring, said spring being stressable to permit said rod to be thrust rearward manually, the full extent determined by the head space to be measured, including support means disposable at the muzzle end of said rifle, and a micrometer head carried by said support means, said micrometer head having a reciprocal element engageable with the outer end of said rod for measuring the length of said travel, said reciprocal element being engageable with the outer extremity of said rod at either limit of travel thereof.

6. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having an end engaging said spring engaging means for maintaining said base in full forward simulated firing position, including means for providing an opposing force engagement for the other end of said spring, said spring being stressable to permit said rod to be thrust rearward manually, the full extent determined by the head space to be measured, including means disposed adjacent to the outward end of said rod for measuring the travel thereof between full forward position to full rearward position as determined by said head space, said measuring means being carried by a support means and disposed adjacent the end of said rod, said support means including a clamp adapted to be secured to said rifle barrel, and a bar slidably carried by said clamp, and means for fixedly securing said bar and clamp in adjusted position relative the outer extremity of said rod.

7. A gauge for measuring the head space of a rifle, comprising a base shaped to simulate a rifle cartridge and being disposable in the firing chamber of the rifle, and a rod elongated to extend through the barrel of the rifle and outwardly of the muzzle thereof, including means for removably securing said rod at its inner end to said base, said rod having a spring engaging means disposed forwardly of the muzzle of the rifle when the rod is inserted in the barrel thereof and is attached to said base, and a spring having one end engaging said spring engaging means for maintaining said base in full forward simulated firing position, including means for providing an opposing force engagement for the other end of said spring, said spring being stressable to permit said rod to be thrust rearward manually the full extent determined by the head space to be measured.

ured, wherein said spring comprises a coil type compression spring and is disposed surrounding an exposed portion of said rod, including a sleeve member slideable on said rod for abutting the other end of said spring, said sleeve member having a force fit in the bore of said rifle to a predetermined position, to provide said opposing force engagement for said spring.
